UNITED STATES PATENT OFFICE.

JACOB M. MARCH, OF PHOENIXVILLE, PENNSYLVANIA.

GARMENT-SUPPORTER.

SPECIFICATION forming part of Letters Patent No. 415,973, dated November 26, 1889.

Application filed June 29, 1889. Serial No. 316,087. (No model.)

To all whom it may concern:

Be it known that I, JACOB M. MARCH, a citizen of the United States, and a resident of Phoenixville, Chester county, Pennsylvania, have invented certain Improvements 5 in Stocking-Retainers, of which the following is a specification.

The object of my invention is to construct a cheap and simple stocking-supporter that 10 will readily fasten the stocking to the under-garment, and that will lie perfectly flat to the limb of the wearer.

In the accompanying drawings, Figure 1 is a view showing the supporter attached to the 15 stocking and under-garment. Fig. 2 is a face view of the supporter. Fig. 3 is a plan view. Fig. 4 is a perspective view showing the supporter open, ready to be secured to the stocking. Fig. 5 is a view of the sup- 20 porter closed. Fig. 6 is a view of the supporter in the form of a garter, and Fig. 7 is a diagram illustrating the application of the supporter.

Referring to the drawings, A A' are two 25 metallic plates preferably struck up from sheet metal and hinged together at a, so as to open, as shown in Fig. 4, the pivot of this hinge a being above the level of the plate. These plates are cut away at c c, and at the 30 ends of each plate are prongs b b, which pass each other, and are preferably tapered, as shown in Fig. 2, thus interlocking when they are fastened in place. Pivoted at e to the section A is a fastening-buckle E, having a 35 head e', which overlaps the portion A' of the retainer, so that when the fastening is moved to the position shown in Fig. 4 the portions of the retainer can be moved upon the hinge; but when the buckle is moved to the position 40 shown in Fig. 5 the retainer is perfectly rigid and cannot work loose. The hinge, as shown in Fig. 3, is above the inner face of the plates A A', so that on the moving of the two parts on the hinge the ends of the prongs b will be 45 thrown apart, allowing one set of prongs to readily enter and pass through the stocking into the under-garment.

To apply the supporter, the device is opened, as shown in Fig. 4, and the prongs b b of the 50 portion A are inserted in the same manner as pins into the material of the stocking and of

the drawers, and when the prongs are forced in position the portion A' is turned over, as shown in Figs. 1 and 5, the prongs b b of this portion entering the fabric of both the stocking and drawer-leg and interlocking with the prongs of the portion A. The fastening is then placed in position, and it will be impossible for the retainer to work loose. 55

In some cases two or more of these retainers can be placed upon the leg, as circumstances require, and in place of the fastening e (shown in Fig. 2) the retainers may be turned, as shown in Fig. 6, and the portions A A' may be provided with loops f f, bands 60 F being passed through these loops, so that if two retainers are used on one stocking the bands F will hold the retainers together, and at the same time keep them flat against the leg and impart sufficient tension to prevent 65 the prongs from becoming disengaged from the garments when the fastening e is dispensed with; but in some cases the fastening e may be attached to the retainers, together with the bands F. The bands F F also prevent 70 the stocking from sagging between the two retainers, as sometimes the stockings are turned over the garter. 75

I claim as my invention—

1. The combination, in a stocking-retainer, 80 of the plates A A', hinged together at the center and having prongs at each end extending toward the pivot-line of the plates, substantially as described.

2. The combination, in a stocking-support, 85 of the plates A A', hinged together at the center, with prongs b b at the ends of each plate, said prongs extending toward the pivot-line of the plates and interlocking with each other, so that the prongs of the retainer will 90 enter the stocking at or about the same point.

3. The combination of the plates A A', pivoted at a, and prongs b b, with a fastening E, pivoted to one of the plates and adapted to pass over and retain the opposite plate, sub- 95 substantially as described.

4. The combination, in a stocking-retainer, of the plates A A', hinged together at the center and having prongs at the ends, the plates having loops, with bands attached to 100 said loops, substantially as described.

5. The combination, in a stocking-retainer,

of two or more fastening devices each consisting of two plates hinged together with serrated inner edge, with bands secured to said plates acting to keep said fastening devices in engagement with the garment, substantially as described.

In testimony whereof I have signed my name

to this specification in the presence of two subscribing witnesses.

JACOB M. MARCH.
